CLAIM

We claim the ornamental design for door handle pull and escutcheon, as shown and described.

DESCRIPTION

FIG. 1 is a front perspective view of a door handle pull and escutcheon according to a first embodiment of the invention;

FIG. 2 is a front elevation view of the door handle pull and escutcheon depicted in FIG. 1;

FIG. 3 is a side elevation view of the door handle pull and escutcheon depicted in FIG. 1;

FIG. 4 is an opposing side elevation view of the door handle pull and escutcheon depicted in FIG. 1;

FIG. 5 is a rear elevation view of the door handle pull and escutcheon depicted in FIG. 1;

FIG. 6 is a top plan view of the door handle pull and escutcheon depicted in FIG. 1;

FIG. 7 is a bottom plan view of the door handle pull and escutcheon depicted in FIG. 1;

FIG. 8 is a front perspective view of a door handle pull and escutcheon according to a second embodiment of the invention;

FIG. 9 is a front elevation view of the door handle pull and escutcheon depicted in FIG. 8;

FIG. 10 is a side elevation view of the door handle pull and escutcheon depicted in FIG. 8;

FIG. 11 is an opposing side elevation view of the door handle pull and escutcheon depicted in FIG. 8;

FIG. 12 is a rear elevation view of the door handle pull and escutcheon depicted in FIG. 8;

FIG. 13 is a top plan view of the door handle pull and escutcheon depicted in FIG. 8;

FIG. 14 is a bottom plan view of the door handle pull and escutcheon depicted in FIG. 8;

FIG. 15 is a front elevation view of a door handle pull and escutcheon according to a third embodiment of the invention;

FIG. 16 is a side elevation view of the door handle pull and escutcheon depicted in FIG. 15;

FIG. 17 is an opposing side elevation view of the door handle pull and escutcheon depicted in FIG. 15;

FIG. 18 is a rear elevation view of the door handle pull and escutcheon depicted in FIG. 15;

FIG. 19 is a top plan view of the door handle pull and escutcheon depicted in FIG. 15;

FIG. 20 is a bottom plan view of the door handle pull and escutcheon depicted in FIG. 15;

FIG. 21 is a front elevation view of a door handle pull and escutcheon according to a fourth embodiment of the invention;

FIG. 22 is a side elevation view of the door handle pull and escutcheon depicted in FIG. 21;

FIG. 23 is an opposing side elevation view of the door handle pull and escutcheon depicted in FIG. 21;

FIG. 24 is a rear elevation view of the door handle pull and escutcheon depicted in FIG. 21;

FIG. 25 is a top plan view of the door handle pull and escutcheon depicted in FIG. 21;

FIG. 26 is a bottom plan view of the door handle pull and escutcheon depicted in FIG. 21;

FIG. 27 is a front elevation view of a door handle pull and escutcheon according to a fifth embodiment of the invention;

FIG. 28 is a side elevation view of the door handle pull and escutcheon depicted in FIG. 27;

FIG. 29 is an opposing side elevation view of the door handle pull and escutcheon depicted in FIG. 27;

FIG. 30 is a rear elevation view of the door handle pull and escutcheon depicted in FIG. 27;

FIG. 31 is a top plan view of the door handle pull and escutcheon depicted in FIG. 27;

FIG. 32 is a bottom plan view of the door handle pull and escutcheon depicted in FIG. 27;

FIG. 33 is a front elevation view of a door handle pull and escutcheon according to a sixth embodiment of the invention;

FIG. 34 is a side elevation view of the door handle pull and escutcheon depicted in FIG. 33;

FIG. 35 is an opposing side elevation view of the door handle pull and escutcheon depicted in FIG. 33;

FIG. 36 is a rear elevation view of the door handle pull and escutcheon depicted in FIG. 33;

FIG. 37 is a top plan view of the door handle pull and escutcheon depicted in FIG. 33;

FIG. 38 is a bottom plan view of the door handle pull and escutcheon depicted in FIG. 33;

FIG. 39 is a front elevation view of a door handle pull and escutcheon according to a seventh embodiment of the invention;

FIG. 40 is a side elevation view of the door handle pull and escutcheon depicted in FIG. 39;

FIG. 41 is an opposing side elevation view of the door handle pull and escutcheon depicted in FIG. 39;

FIG. 42 is a rear elevation view of the door handle pull and escutcheon depicted in FIG. 39;

FIG. 43 is a top plan view of the door handle pull and escutcheon depicted in FIG. 39;

FIG. 44 is a bottom plan view of the door handle pull and escutcheon depicted in FIG. 39;

FIG. 45 is a front elevation view of a door handle pull and escutcheon according to an eighth embodiment of the invention;

FIG. 46 is a side elevation view of the door handle pull and escutcheon depicted in FIG. 45;

FIG. 47 is an opposing side elevation view of the door handle pull and escutcheon depicted in FIG. 45;

FIG. 48 is a rear elevation view of the door handle pull and escutcheon depicted in FIG. 45;

FIG. 49 is a top plan view of the door handle pull and escutcheon depicted in FIG. 45; and,

FIG. 50 is a bottom plan view of the door handle pull and escutcheon depicted in FIG. 45.

The broken line depiction of structure is included for the purpose of illustrating environment and forms no part of the claimed design.
